UNITED STATES PATENT OFFICE.

WILLIAM E. RINES, OF ARLINGTON, MASSACHUSETTS.

SASH-FASTENER.

SPECIFICATION forming part of Letters Patent No. 280,400, dated July 3, 1883.

Application filed May 12, 1883. (No model.)

To all whom it may concern:

Be it known that I, WILLIAM EDWARD RINES, of Arlington, in the county of Middlesex, of the Commonwealth of Massachusetts, have invented a new and useful Improvement 5 in Railway-Car Window-Sash Fasteners; and I do hereby declare the same to be described in the following specification, and represented in the accompanying drawings, of which—

10 Figure 1 is a side elevation, and Fig. 2 a vertical section, of a fastener of my improved kind as applied to a window-sash and its frame, such sash and frame being shown in part in such figures.

15 In the said drawings, A denotes one of the side bars of the sash-frame, while B is the next contiguous part of the window-frame.

20 My invention is to fasten the window-sash when closed, and to sustain it when raised to any altitude within the range of its vertical movement.

25 In the drawings, C denotes the case of the fastener, such case being proved with perforated flanges *a a* to enable it to be fastened to the sash by means of screws going through such flanges and screwed into the sash. This case, arranged near the outer edge of the sash, has within its lower part a bolt or latch, G, which extends out of the case in manner as shown, and is provided with a spring, H, to 30 advance it automatically. A knee-lever, I, having its longer arm projecting through a slot, b, in the case, is fulcrumed within the case, (the fulcrum being shown at *g*.) and has its shorter arm extended into a notch, c, in 35 the bolt. This bolt is to operate with the triangular projection *d* of the catch K, fastened to the window-frame in which the sash runs.

40 Above the bolt there is an eccentric, D, which projects out of the case and bears against the window-frame. This eccentric turns on a pivot, e, and is provided with an arm, f, that projects from it (the said eccentric) in manner as represented. A spring, F, arranged in

the case and with respect to the said arm *f* in 45 manner as shown, serves to depress the arm in order to force the eccentric against the window-frame. A lever, E, fulcrumed in the case (the fulcrum being shown at *h*) and having its shorter arm curved upward and extending out 50 of the case in manner as represented, has its shorter arm projected underneath and against the arm *f* of the eccentric.

A person, in order to raise the sash, is to 55 seize the longer arms of the two levers E and I between the first and second fingers of his hand, placing the first one—viz., the thumb—on the lever E, and the second or index finger under the lever I. Next he is to force the levers toward each other, or simply pull upward the 60 lower one. This will cause the bolt G to be retracted and the sash to rise. Having elevated the sash to the desired altitude, he should release his hold of the levers, or the lower one, in which case the eccentric D, by its action 65 against the frame in which the sash runs, will hold the sash in its position. In order to depress the sash, the longer arm of the lever E is to be forced downward, in which case the eccentric will be borne away from the frame and 70 the sash may be lowered. In the descent of the sash the bolt G will be borne against the triangular projection *d*, and by such will be forced backward until such bolt may pass below the said projection, which having taken 75 place the bolt by its spring will be shot forward underneath the projection, and with such will lock the sash down.

I claim—

The sash-fastener substantially as described, 80 consisting of the case C, bolt G, spring H, knee-lever I, eccentric D, the arm *f*, spring F, and lever E, arranged and adapted essentially and to operate as set forth.

WILLIAM EDWARD RINES.
